CLAIM

The ornamental design for a freezer organizing kit as shown and described.

DESCRIPTION

FIG. 1 is a perspective view of a freezer organizing kit, showing my new design.

FIG. 2 is a top view of the claimed design.

FIG. 3 is a front view of the claimed design.

FIG. 4 is a rear view of the claimed design.

(Continued)

FIG. 5 is a bottom view of the claimed design.
FIG. 6 is a left side view of the claimed design; and,
FIG. 7 is a right side view of the claimed design.
